(57) **CLAIM**

The ornamental design for a golf marker-green reading system, as shown and described.

DESCRIPTION

This application is a design application related to the U.S. Application entitled Green Reader / Golf Ball Marker and Method of Using Same, filed August 24, 2004.

FIG. 1 is a top perspective view of the golf marker-green reading system;

FIG. 2 is a side elevational view thereof; all other sides being identical;

FIG. 3 is a top plan view thereof;

FIG. 4 is a bottom plan view thereof;

FIG. 5 is a perspective of a second embodiment of the golf marker-green reading system;

FIG. 6 is a side elevational view of FIG. 5; the other sides being identical; and,

FIG. 7 is a bottom plan view of FIG. 5.

It should be understood that the labels used herein for describing orientation (e.g., front, rear, top, bottom, right and left) are merely for reference, and the design may be disposed in any manner and still be within the scope of the present invention.

The broken line showing is for illustrative purposes only and forms no part of the claimed design.
